UNITED STATES PATENT OFFICE.

JOSE MARIA MARISCAL AND ASCENSION LAMORANO GUTIERREZ, OF SONORA, ARIZONA.

RIBBON-BOLT HOLDER.

1,281,184.

Specification of Letters Patent.

Patented Oct. 8, 1918.

Application filed August 23, 1917. Serial No. 187,796.

To all whom it may concern:

Be it known that we, JOSE MARIA MARISCAL, a citizen of the United States, and ASCENSION LAMORANO GUTIERREZ, a citizen of Mexico, residing at Sonora, in the county of Pinal, State of Arizona, have invented a new and useful Ribbon-Bolt Holder; and we do hereby declare the following to be a full, clear, and exact description of the invention, such as will enable others skilled in the art to which it appertains to make and use the same.

The present invention relates to a ribbon bolt holder, and has for its object to provide a device of this character which embodies novel features of construction whereby it can be expanded and contracted to fit different sizes of ribbon bolts, and will securely clamp the free end of the ribbon against the bolt, thereby avoiding the annoyance which is incident to fastening the free end of the ribbon with a pin each time a length of ribbon is removed from the bolt.

Further objects of the invention are to provide a ribbon bolt holder which can be formed from a single length of wire and is inexpensive in its construction, which can be quickly applied to a ribbon bolt or removed therefrom, which does not interfere with handling the ribbon bolt in the usual manner and unrolling the desired lengths of ribbon therefrom, and which will operate in an effective manner to prevent waste due to the ends of the ribbon becoming soiled and shop worn.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is an end view of a ribbon bolt having the device applied thereto.

Fig. 2 is a top plan view of the ribbon bolt holder, showing the same as detached from the ribbon bolt.

Fig. 3 is a top plan view of a ribbon bolt with the holder or clamping device applied thereto, a form of detachable handle being shown as applied to the device for holding the bolt when unrolling a length of ribbon therefrom.

Corresponding and like parts are referred to in the following description and indicated in all the views of the drawings by the same reference characters.

Referring to the drawings, which illustrate one embodiment of the invention, the reference character A designates a conventional ribbon bolt, the free end 1 of the ribbon being shown as clamped against the sides of the ribbon bolt by means of a holder or clamping device embodying the invention, thereby avoiding the annoying necessity of fastening the free end of the ribbon to the bolt by means of pins. The holder or clamp may be formed of a single length of wire, and includes a looped clamping head 2 which is arranged to hold the free end of the ribbon yieldably against the bolt. A pair of spring arms 3 diverge rearwardly from the looped clamping head 2 and are curved upon the arc of a circle having substantially the same curvature as the periphery of the ribbon bolt. These diverging arms 3 have a spring action and are adapted to be sprung apart to a greater or less degree to admit of the device being applied to larger or smaller ribbon bolts. The ends of the diverging arms 3 carry side arms 4 which project radially with respect to the arc upon which the diverging arms are curved, the wire being coiled at the junction of the side arms 4 and diverging arms 3, as indicated at 5. A resilient connection is thus provided between the arms 3 and 4 so that the latter can readily be sprung outwardly into position to fit against the sides of the ribbon bolt A. The free ends of the side arms 4 terminate in pivot fingers 6 which project laterally therefrom and are adapted to be inserted into the ends of the axial opening 7 of the ribbon bolt. The coils 5 also tend to hold the clamping head 2 at the ends of the diverging arms 3 in a yielding engagement with the outer surface of the ribbon bolt, said head being adapted to be utilized, as previously explained, for the purpose of clamping the free end of the ribbon in position against the bolt. The side arms 4 may be provided with rollers or sleeves 8 which are held in position between the crimped shoulders 9, and are adapted to engage the ends of the bolt to prevent binding and unnecessary friction when the bolt is rotated within the clamping or holding device to unroll a length of ribbon therefrom. When unrolling a length of ribbon

the device may be conveniently grasped by placing the thumb and forefinger of one hand in engagement with the coils 5, thereby holding the device against rotation as the ribbon is unrolled from the bolt. Should this not be convenient, a separate handle 10 might be employed, said handle having a looped or U-shaped formation, and being provided at its ends with laterally projecting pivot arms 11 adapted to engage pivot eyes 12 formed at the outer ends of the side arms 4 by crimping the wire at points adjacent the coils 5. The U-shaped handle 10 can be easily flexed to provide for inserting the pivot arms 11 into the pivot eyes 12, or removing them therefrom. One handle can thus be employed in connection with a large number of ribbon bolts, being attached to the clamping device of the bolt or removed therefrom, as desired. When a ribbon bolt is held by means of a handle 10 the free end of the ribbon can be grasped and withdrawn from the bolt without difficulty.

Having thus described the invention, what we claim as new and desire to secure by Letters Patent, is:—

1. A ribbon bolt holder formed of wire and including a clamping head adapted to hold the free end of the ribbon yieldably against the bolt, a pair of diverging spring arms projecting rearwardly from the clamping head and curved to fit around the bolt, side arms carried by the ends of the diverging arms and projecting radially inward with respect to the arc upon which the diverging arms are curved, said side arms terminating in laterally bent pivot pins and being each provided at an intermediate point in its length with spaced crimps, and an anti-friction roller journaled upon each of the side arms between the spaced crimps thereof.

Copies of this patent may be obtained for five cents each, by addressing the "Commissioner of Patents, Washington, D. C."

2. A ribbon bolt holder formed of wire and including a clamping head adapted to hold the free end of the ribbon yieldably against the bolt, a pair of diverging spring arms projecting from the head and curved to fit around the bolt, side arms carried by the diverging arms and projecting radially inward from the end of the arc upon which the diverging arms are curved, the outer ends of the side arms being crimped to provide eyes, while the inner ends of the side arms terminate in laterally extending pivot pins, and a detachable handle member provided with laterally extending pivot arms adapted to be sprung into and out of engagement with the before mentioned eyes of the side arms.

3. A ribbon bolt holder formed of wire and including a clamping head adapted to hold the free end of the ribbon yieldably against the bolt, a pair of diverging spring arms projecting from the head and curved to fit around the bolt, side arms carried by the diverging arms and projecting radially inward from the end of the arc upon which the diverging arms are curved, the outer ends of the side arms being provided with eyes, while the inner ends thereof terminate in laterally projecting pivot pins, and a detachable U-shaped handle provided at its ends with laterally extending pivot arms adapted to be brought into and out of engagement with the eyes of the side arms by flexing the U-shaped handle.

In testimony whereof we have signed our names to this specification in the presence of two subscribing witnesses.
